UNITED STATES PATENT OFFICE

REGINALD HARRY FILMER, OF CLERKENWELL, ENGLAND

FOLDING BOX

Application filed April 26, 1930, Serial No. 447,543, and in Great Britain July 6, 1929.

The invention relates to folding boxes generally made of cardboard or like material, and has for its object to construct a box which may be folded and erected with minimum expenditure of time and in which the bottom is extremely strong due to the fact that improved means are provided for locking the bottom upon its support.

The present invention relates to that type of folding box in which the vertical sides are adapted to fold together into two planes in which a support for the bottom is connected to two of the vertical sides by hinges, generally consisting of creases, and said support has a crease dividing it into two parts and allowing these two parts to fold together as the vertical sides are being folded. In such boxes the bottom is hinged to two other vertical sides and it has a crease dividing it into two parts which fold together as the other parts are being folded. To the free sides of the bottom are hinged flaps which have a normal tendency to spring outwards against the vertical sides of the box.

According to the present invention the bottom of the box is held down upon its support by means of a catch, that is to say a retaining device, located in a vertical corner between the sides, and acting upon the upper surface of that corner of the bottom which is free and adapted to rise as the box is folded. When the invention is applied to boxes that are hexagonal in plan there are two free corners of the bottom and a separate catch, acting on the upper surface of the bottom, is employed to hold down each of the free corners.

Each catch has a single hinged portion which is moved into a position to allow the bottom of the box to be placed upon its support, after which the hinged portion is moved into a position to retain the bottom of the box thereon.

The invention is illustrated in the accompanying drawings in which:—

Fig. 1 is a plan of the body of a square box and

Fig. 2 is a side elevation of the same in its folded condition partly broken away.

Fig. 3 is an underside view of the box shown in Fig. 1, and

Fig. 4 is an underside view of a box showing a modification.

Fig. 5 is an elevation within the box shown in Fig. 1 seen in the direction of the arrow and showing one form of retaining device for holding down the bottom.

Fig. 6 is a plan of a blank, drawn to a smaller scale, made in a single piece, to produce a square box.

Fig. 7 is a plan of a square box showing a modified retaining device, and Fig. 8 is a section on the line 8—8 through the box shown in Fig. 7 seen in the direction of the arrow in that figure.

Fig. 9 is a plan of an oblong box and Fig. 10 is an underside view of the same.

Fig. 11 is a side elevation of the box shown in Figs. 9 and 10, in its folded condition, two sides and part of the catch being omitted to show the parts clearly.

Fig. 12 is a plan of a hexagonal box.

Fig. 13 is a section on the line 13—13 of Fig. 12.

Fig. 14 is an underside view of the box shown in Fig. 12.

Fig. 15 is a plan of a blank, made in a single piece to produce a hexagonal box.

As shown in Figs. 1, 2, 3 and 5, the box is formed with four vertical walls 2, 3, 4, 5. To the walls 2 and 5 is hinged, by means of creases, a triangular shaped support 6 which is creased at 7 thereby enabling the parts on each side of said crease to fold towards each other when the sides 2 and 3 are moved towards the sides 5 and 4. This support 6 is indicated by the dotted line in Fig. 1 and is seen fully in Fig. 3.

To the sides 3 and 4 is hinged a bottom 8 which is creased at 9 to allow the same to fold upwards when the box is folded. The bottom 8 is provided in the construction shown in Fig. 1 with flaps 10 on the sides 2 and 5 and flaps 100 on the sides 3 and 4. This bottom, as shown in Figs. 1 to 3, is in fact a separate piece of material and the two flaps 100 are sewn to the vertical sides 3 and 4. The flaps 10 have a tendency to spring outwards against the sides 2 and 5, when the

box is erected for use. The friction of these flaps 10 and of the loose edges of the bottom 8 against the sides 2 and 5 is sufficient to hold the bottom in position upon the support 6 prior to the locking portion herein-after described.

The crease 7 always bisects an angle containing a catch, hereinafter described, and the crease 9 bisects an opposite angle.

10 The folding support 6, as shown in Fig. 1, has flaps 11 which are sewn to the two vertical sides 2 and 5.

15 The box, the supports and the folding bottom may, however, be made from a single piece of material, as shown in Fig. 6, providing it is capable of folding in the manner hereinbefore described.

20 The support 6 may fold either within two of the vertical sides, as shown in dotted lines in Fig. 2, or it may fold downwards as shown in full lines and partly broken away. The bottom 8 and its side flaps 10 fold upwards, as shown in Fig. 2. The flaps 10 may fold, as shown in Fig. 2, into the 25 same plane as the two portions of the folded bottom 8.

20 The support 6, instead of being triangular as shown in Fig. 3, may have a portion of the triangle cut away and may thus be 30 rendered L shaped, as shown in Fig. 4, otherwise the box is the same as that shown in Figs. 1 to 3.

35 Fig. 5 shows one method of constructing the retaining device which, as shown, consists of a strip of cardboard 12 which is sewn at its upper part at 13 to the adjacent sides 2 and 5. This strip of cardboard is preferably equal in length to the vertical height of the sides, as shown, to strengthen the corner of the box, and it is creased along its 40 central vertical line at 14 so that it may fold with the sides to which it is attached. A horizontal crease 15 enables the lower part 16 of the strip 12 to be bent upwards into the 45 position shown in Fig. 2, in which position the bottom 8 of the box may be pushed down on to the support 6. The part 16 is then folded downwardly against the upper surface of the bottom 8 and against the flaps 50 10, as seen clearly in Fig. 5 to lock the said bottom upon its support 6.

55 In the construction shown in Fig. 7 one of the vertical walls 17 of the box is bent inwards to form a vertical flap 18, the parts 17 and 18 being provided with a single crease at the bend to enable the part 18 to be readily moved upon the said crease as upon a hinge. In this modification the bottom 8 is provided with a diagonal crease 9 and flaps 10 60 as in Fig. 1. The vertical flap 18 is moved against the side 19 of the box to enable the bottom 8 to be pressed down on to a support 6, similar to that shown in Figs. 1 to 3, after which the vertical flap 18 is moved out into 65 the position shown in Fig. 7 between the two

vertical flaps 10, 10. The lower edge of the vertical flap 18 bears against the upper surface of the bottom 8 of the box, as shown in Fig. 8, and holds it down against the support 6 carried by the vertical sides 17 and 19.

70 When the box shown in Fig. 7 is filled with goods the vertical flap 18 may move, as indicated by the dotted line, against either of the flaps 10 and against one of the vertical sides 17 and 19. It is only necessary to move the flap 18 against one of the flaps 10 and to move the other flap 10 downwards to allow the bottom 8 to rise as the vertical sides of the box are caused to approach each other and as the support 6 for the bottom 8 of the box is caused to fold either between the vertical sides, as shown in Fig. 2 in dotted lines, or beneath the vertical sides as shown in full lines. 20, 20 are two flaps on the support 6 for the bottom, which flaps are shown secured to the outside of the sides 17 and 19.

75 Fig. 6 shows a blank cut from a sheet of cardboard suitable for making the body of a box (excluding the catch) having all the characteristics of the box shown in Figs. 1, 2 and 3, similar parts being indicated by similar numerals in all these views. The flap 21 is connected to the side 2 by a crease 22. The sides 2, 3, 4 and 5 are connected by creases 23. The bottom 8 is connected to the side 4 by a crease 24. The flap 100 is connected to the bottom 8 by a crease 25. The two flaps 10 are connected to the bottom 8 by creases 26, 26. The triangular part 6, which forms the support for the bottom 8 is connected by a crease 27 to the side 2. The flap 28 is connected to the part 6 by the crease 29.

80 To construct the box the four sides are folded on the creases 23 into a square and the flap 21 is secured to the vertical edge of the side 5 in the position indicated by the dotted lines. The flap 100 is then secured to the adjacent vertical side 3 in the position indicated by dotted lines. The two flaps 10, 10 are turned upwards within the sides 2 and 5 but are not fixed to these sides. Finally the flap 28 creased to the triangular support 6 is connected to the lower edge of the side 5 in the position indicated by the dotted lines. Such a box will have a separate vertical strip 12, 110 16 forming the retaining device sewn in the angle formed by the sides 2 and 5, as shown in Fig. 5.

85 In the oblong box shown in Figs. 9 to 11 similar parts are indicated by similar numbers to those employed in Figs. 1 to 3. In this box the crease 9 bisects the angle between the sides 3 and 4 but does not enter the opposite angle in which the retaining device 12, 16 is fixed. The crease 7 bisects the angle between the sides 2 and 5 and the support 6 passes diagonally across the box as seen in Fig. 10 and as shown by a dotted line in Fig. 9. The two parts of the bottom 8 on each side of the crease 9 fold closely together and the 120 130

two parts of the support 6 on each side of the crease 7 likewise fold closely together. One of the flaps 10 is folded intermediate of its ends, one portion being vertical and one horizontal as seen clearly in Fig. 11. The other flap 10, that seen on the left hand side of the bottom 8 in Fig. 11, is in the same plane as that side of the bottom to which it is attached. Part of the retaining device 16 is shown 10 raised in Fig. 11 to allow the bottom 8 and support 6 to fold.

The hexagonal box shown in Figs. 12 to 14 is made from the blank shown in Fig. 15. The vertical sides 29 and 32 are connected by 15 creases directly to opposite sides of the bottom 8. The vertical sides 30 and 34 are connected by creases to the side 29. The vertical sides 31 and 33 are connected by creases to the side 32. The bottom 8 has a crease 9 to allow it to fold and it rests at opposite points upon two supports 6 each having a crease 7 to allow it to fold. Each support 6 is made in two parts. The two parts of one support are 25 connected by creases to the sides 30 and 31 and the two parts of the other support 6 are connected by creases to the sides 33 and 34. The four parts forming the two supports are all marked 6 in Fig. 15. Two of the 30 parts 6 in this figure carry flaps 35 which are sewn to the two other parts 6 as seen in Fig. 12 where the bottom 8 is broken away to show one connection.

The flaps 10, which fit up against the 35 inner walls 30, 31, 33, 34, are necessarily triangular as shown in Figs. 13 and 15, whereas in the constructions shown in Figs. 1 to 11 the two longer sides are parallel.

The sides 30 and 31 as well as the sides 33 40 and 34 are shown as connected by vertical strips 36 which are shown sewn at 37 to two adjoining edges in Fig. 13. Each strip 36 has a vertical crease 38 to allow the sides 30 and 31 to move towards each other.

45 The folding catches 12, 16 are the same construction as shown in Figs. 1 to 5 and bear by their lower edges upon the upper surface of the bottom 8 when the box is in open position as shown in Fig. 13.

50 What I claim as my invention is:—

1. A folding box having in combination vertical sides adapted to fold towards each other, a bottom connected by creases to two vertical sides, a crease in the bottom bisecting the angle between the sides to which the bottom is connected, a support for the bottom connected by creases to two other vertical sides, a crease in the said support bisecting the angle between the sides to which the support is connected, a folding retaining device in the form of a strip fixed in the angle between the sides by which the support is carried and a vertical crease in said strip, in contact with said angle, to allow the sides of the box on each side of said crease to fold

towards each other, the lower edge of the folding retaining device pressing against the upper surface of the bottom when the box is in open position and the retaining device folding to allow the box to be collapsed. 70

2. A folding box having a folding bottom support, a folding bottom, a retaining member placed in the angle between the sides by which the folding bottom support is carried 75 and acting against the upper surface of the bottom to hold this latter securely against its folding support, and a horizontal fold in the retaining member whereby the portion of the retaining member below said fold which presses against the upper surface of the bottom when the box is in open position may be folded back on itself to allow the box to be collapsed. 80

3. A folding box having in combination 85 vertical sides adapted to fold towards each other, a folding bottom connected by creases to two vertical sides, a folding support for the bottom connected by creases to two other vertical sides, a folding retaining device 90 having a single vertical crease fixed in the angle between the sides by which the support is carried, a horizontal crease in said retaining device, the said retaining device pressing by its lower edge upon the upper surface of the folding bottom when the box is in open position and being folded back on itself to allow the box to be collapsed. 95

4. A folding box having in combination 100 vertical sides adapted to fold towards each other, a folding bottom connected by creases to two vertical sides, a folding support for the bottom connected by creases to two other vertical sides, a folding retaining device 105 having a single vertical crease fixed with its crease in contact with the angle between the sides by which the support is carried, the said retaining device pressing by its lower edge upon the upper surface of the folding bottom when the box is in open position and being folded back on itself to allow the box 110 to be collapsed.

In witness whereof I have hereunto set my hand.

REGINALD HARRY FILMER. 115
